UNITED STATES PATENT OFFICE.

WILLIAM S. SAMPSON, OF OAKLAND, CALIFORNIA.

DRAWING-RULER.

1,185,439.

Specification of Letters Patent. Patented May 30, 1916.

Application filed December 30, 1915. Serial No. 69,369.

To all whom it may concern:

Be it known that I, WILLIAM S. SAMPSON, a citizen of the United States, and a resident of Oakland, in the county of Alameda and State of California, have invented 5 certain new and useful Improvements in Drawing-Rulers, of which the following is a specification.

My invention is an improvement in drawing rulers, and the invention has for its object to provide a ruler of the character specified, adapted for the use of architects, draftsmen and the like, wherein a ruler is mounted on a drawing board or table in such 10 manner that it may be moved from end to end of the table or board, while retaining its transverse position with respect to the board or table, and wherein the ruler is provided with a guide extending longitudinally 15 thereof, for guiding a carriage with respect to the ruler, and wherein a second ruler is connected with the carriage in such manner 20 as to permit the said ruler to be held at varying angles with respect to the first named 25 ruler.

In the drawings: Figure 1 is a perspective view of the improved ruler in connection with a drawing table; Fig. 2 is an edge view; Fig. 3 is a partial top plan view, and 30 Figs. 4 and 5 are sections on the lines 4—4 and 5—5, respectively, of Fig. 3, Fig. 4 looking in the direction of the arrows adjacent to the line.

The present embodiment of the invention 35 is shown in connection with a drawing board or table 1 of rectangular form, and of sufficient size, and the said table is pivoted intermediate its ends to uprights or standards 2, each of which has a base 3, and the standards 40 or uprights are connected by a cross bar 4, and are braced against the cross bar by inclined braces 5.

The table is, as before stated, pivotally connected with the standards or uprights to 45 permit the table to be swung with respect to the standards or uprights, and the table is held in adjusted position by means of an arc-shaped slotted arm 6, which is connected to one end of the table at one side thereof, 50 and the slot of the arm is engaged by a headed pin or set screw 7 on one of the uprights or standards, to hold the table in adjusted position.

A pair of sprocket wheels 8 is journaled 55 at each end of the table, the wheels at each end having their axes in alinement, and the

members of the pairs register at each side of the table, and support a sprocket chain 9. The wheels at the bottom or rear of the table are mounted on independent stub shafts 60 10, while the wheels 8 at the top or front of the table are secured to the ends of a shaft 10^a, which extends the full width of the table and the shafts 10 and 10^a are mounted in bearings 11 on the board or table. Each 65 chain is provided with an upstanding beading lug 12, the lugs 12 being in register transversely of the table. A shaft or roller 13 is arranged between the chains, on the upper surface of the table, and headed 70 screws 14 are passed through the lugs at each side of the table, and into engagement with the ends of the roller to mount the roller between the chains. The lugs 12 are of such height, that the roller 13 will be 75 spaced slightly above the upper surface of the table, to permit the roller to be moved longitudinally of the table by the chain.

A ruler 15 is connected to the shaft, the 80 said ruler having its front or upper edge beveled as shown at 16, and having at its rear edge open bearings 17, for engaging the shaft 13. The beveled edge of the ruler is graduated, as shown more particularly in Fig. 2, in units of any desired character, and the said ruler is provided in its upper face 85 with a longitudinally extending groove 18 extending the full length of the ruler.

A carriage or slide plate 19 is mounted on 90 the ruler, for movement longitudinally thereof, and the said plate has a rib 20 on its under face and near its rear edge, and it will be noticed from an inspection of Fig. 5, that one wall of the rib is undercut. The rib 95 is of a size to fit within the groove 18, and to move in the groove with the under surface of the plate engaging the upper surface of the ruler, and a holding plate 21 is provided for preventing disengagement of the carriage or sliding plate 19.

The upper surface of the ruler 15 is enlarged or rabbeted in front of the groove 18, and the holding plate fits within the rabbet or counterbore, and engages the undercut wall of the rib, to hold the slide plate in 105 place. The plate 21 is held in place by screws 22 or the like, as shown in Figs. 3 and 5 of the drawing, and since the rear edge of the plate engages the undercut wall of the groove, the plate cannot move upward to 110 disengage the rib 20 from the groove.

A ruler 23 is connected to the plate 19,

by means of a pivot pin or rivet 24, and it will be noticed from an inspection of Fig. 2, that the ruler 23 has both side edges beveled, and one of the side edges is provided 5 with a scale, as shown. The edge of the plate 19 remote from the ruler 15 is rounded or curved on an arc whose center is the pivot pin 24. At the said edge the plate 19 has an arc shaped slot 25, and a headed pin or screw 10 26 on the ruler 23 is passed through the slot and into engagement with the ruler 23, to hold the ruler in adjusted position with respect to the plate 19.

The particular arrangement of the rulers 15 and 23 permits the user to dispense with the ordinary T-square and the triangles, since an angle of any desired degree may be laid off with the rulers 15 and 23.

The roller or shaft 13 cannot change its 20 position transverse to the table, because of the fact that the chains at each side move together. By means of this mounting, the ruler 15 may move from one end of the table to the other, and cannot become displaced 25 with respect to the table.

The ruler 23 may be moved as indicated in dotted lines in Fig. 3, to hold any desired angular position with respect to the ruler 15. The table may be adjusted by means of 30 the elements 6—7, but it is obvious that the improved ruler might be mounted on any drawing table.

I claim:

1. In combination with a drawing table, 35 of a shaft journaled transversely of the table at one end thereof, sprocket wheels secured to the ends of the shaft, a sprocket wheel journaled at the other end of the table at each side thereof and in register with the ad- 40 jacent sprocket wheel of the shaft, sprocket chains mounted on the wheels at each side of the table, each chain having an upstanding bearing lug, and the lugs of the chains being in alinement transverse to the table, a 45 roller held in the lugs, a ruler detachably connected with the roller and movable therewith, said ruler having a guide groove in its upper face, a slide plate having a rib for engaging the groove, and a second ruler piv- 50 oted to the slide plate to swing to either side thereof and having means for holding the said ruler in adjusted position, the first named ruler having means for preventing disengagement of the rib of the slide plate.
2. In combination with a drawing table, 55 of a shaft journaled transversely of the table at one end thereof, sprocket wheels secured to the ends of the shaft, a sprocket wheel journaled at the other end of the table 60 at each side thereof and in register with the

adjacent sprocket wheel of the shaft, sprocket chains mounted on the wheels at each side of the table, each chain having an upstanding bearing lug, and the lugs of the chains being in alinement transverse to the table, a roller held in the lugs, a ruler detachably connected with the roller and movable therewith, said ruler having a guide groove in its upper face, a slide plate having a rib for engaging the groove, and a second ruler pivoted to the slide plate to swing to either side thereof and having means for holding the said ruler in adjusted position. 65 70

3. In combination with a drawing table, 75 of a shaft journaled transversely of the table at one end thereof, sprocket wheels secured to the ends of the shaft, a sprocket wheel journaled at the other end of the table at each side thereof and in register with the adjacent sprocket wheel of the shaft, sprocket 80 chains mounted on the wheels at each side of the table, each chain having an upstanding bearing lug, and the lugs of the chains being in alinement transverse to the table, a roller held in the lugs, a ruler detachably 85 connected with the roller and movable therewith, a slide mounted for movement longitudinally of the first named ruler, and a second ruler pivoted to the slide and having means for holding the said second ruler in 90 adjusted position with respect to the slide.

4. In combination with a drawing table, 95 of a shaft journaled transversely of the table at one end thereof, sprocket wheels secured to the ends of the shaft, a sprocket wheel journaled at the other end of the table at each side thereof and in register with the adjacent sprocket wheel of the shaft, sprocket 100 chains mounted on the wheels at each side of the table, a roller mounted between the chains and connected with the chains to move therewith, a ruler detachably connected with the roller, a slide movable on the ruler from end to end thereof, and a second ruler pivoted to the slide and having 105 means for holding the same in adjusted position with respect to the slide.

5. In combination with a drawing table, 110 of a roller arranged transversely of the table, means in connection with the table for moving the roller from end to end of the table and for constraining the roller to move in a position transverse to the table, a ruler detachably connected with the roller, a slide mounted to move longitudinally of the ruler, 115 and a second ruler pivoted to the slide.
